UNITED STATES PATENT OFFICE.

J. B. STACKPOLE, OF BOSTON, MASSACHUSETTS.

DRAWING AND CAMERA TABLE.

Specification forming part of Letters Patent No. 40,647, dated November 17, 1863.

To all whom it may concern:

Be it known that I, J. B. STACKPOLE, of Boston, county of Suffolk, and State of Massachusetts, have invented a new and Improved Camera and Draftsman's Table; and I do hereby declare that the following is a full and exact description thereof, reference being had to the accompanying drawings, and to the letters of reference marked thereon.

The nature of my invention consists in so arranging the top of a table that it can be easily raised or lowered at will, and at the same time set at any desired angle with the horizon.

To enable others skilled in the art to make and use my invention, I will proceed to describe its construction and operation.

Drawing No. 1 is a perspective view; No. 2, side elevation; No. 3, longitudinal section through center of table.

Similar letters refer to similar parts.

A A A is the body of the table; B, stationary top of table; C, folding board, connected with B by the hinges *c c*, and with movable top D by hinges *d d*; D, adjustable top of table; I I, adjusting-standards, (by which D is raised and lowered,) connected with barrel *k* by the cords *i i*; Q, crank by means of which the barrel *k* and the standards I I are operated; K, ratchet-wheel, connected with barrel *k*; Q, pawl for holding the ratchet-wheel

K; M, lever for raising the pawl; J, adjusting-standard, (by which the fold C, and thus D, is raised and lowered,) connected with the barrel *l* by the cord *j*; R, crank by means of which the barrel *l* and the standard J are operated; L, ratchet-wheel, connected with the barrel *l*; N, lever for raising the pawl; P, pawl for holding the ratchet-wheel L; H, cross-piece connecting legs of table and giving support to boxes F F, in which the standards I I traverse; G, cross-piece connecting legs of table and giving support to box E, in which I traverses.

Instead of the barrel and cord, as described above, the adjusting-standards may be operated by ratchet and pinion, in which case the standards would require a ratchet-piece attached to them for that purpose.

What I claim as my invention, and desire to secure by Letters Patent, is—

The combination of the adjusting-standards J I I (operated either by means of the barrel and cord or by ratchet and pinion) with the double folding boards D and C, substantially as described, and for the purpose herein set forth.

J. B. STACKPOLE.
